UNITED STATES PATENT OFFICE.

HENRY DEMMICK, OF NEW YORK, N. Y., ASSIGNOR TO HIMSELF AND PETER H. JACKSON, OF SAME PLACE.

IMPROVEMENT IN FLASKS FOR CASTING IRON COLUMNS.

Specification forming part of Letters Patent No. 29,745, dated August 21, 1860.

To all whom it may concern:

Be it known that I, HENRY DEMMICK, of the city and State of New York, have invented and made a certain new and useful Improvement in Flasks for Molding Columns and Similar Articles; and I do hereby declare that the following is a full, clear, and exact description of the construction and operation of the same, reference being had to the annexed drawings, making part of this specification, wherein—

Figure 1 is a plan of my said flask. Fig. 2 is a side elevation of the same. Fig. 3 is a cross-section thereof, and Fig. 4 is a cross-section showing one of the sides laid over ready for dressing.

Similar marks of reference denote the same parts.

In molding columns it has been usual heretofore to pack the sand around the pattern, and then take out the same, dress the surface of the mold, and then lay in the core.

In the dressing of the sides of the mold as they stood in a vertical position, particularly with square or box columns, great inconvenience is experienced on account of the small amount of room and the unhandy position; hence the sides of the mold have been fitted to lift off with a crane, in order to expose the face to inspection and dressing where there were imperfections. This was always done at the risk of the whole sand face falling off by any jar, and also at the risk of not returning it exactly to the former position. Besides this, great difficulty was experienced in introducing the core, particularly with box-columns finished or paneled on all four sides, and said core had to be parallel, or nearly so, or it could not be lowered into place between the two standing sides.

The nature of my said invention consists of cheek-pieces hinged onto the bottom part or the "nowel," whereby the sides can be turned down when molded, the surface inspected and dressed, the core put in place after one side is turned up, and then the other side is turned up, and the "cope" is laid in place, and the casting made in said flask.

In the drawings, *a* is the nowel formed of the desired size and shape. *b b* are the cheek-pieces, hinged to *a* at *c c*, and *d* is the cope. These parts are to be provided with the nec-

essary ring bolts or eyes *e e*, by which they may be hoisted or lowered, and the nowel and cope have the usual cross-bars to sustain the sand. The cheeks *b b* are to be formed of two pieces, as shown, so that by the removal of one the flask could be used for a very small column; but by the separation of these pieces a bar, *o*, as seen in the section, Fig. 6, of greater or less width, can be introduced, and the whole secured by the clamps and screws *f f*.

g is a sand-cleat introduced on the inner face of the cheeks *b b*, near the bottom edge thereof. Said cleats *g g* are attached by bolts, so that I can raise them up, in order to mold columns of less size by bringing the pattern *k* above the cope *a*, thereby extending the capacity of my mold and avoiding the necessity of having a separate flask for each column; and *h h* are flanges, made with ribbed edges and dovetail bases, setting between ribs cast on the inside of the cheeks *b b*. (See plan, Fig. 5.) By this mode of connection these sand-flanges can be removed and others substituted, either longer or shorter, wider or narrower, according to the size of column, so as to come sufficiently near the pattern; and in cases where projecting ornaments occur these metallic sand-cleats may be removed entirely, or shorter ones substituted.

i i are holes in the flanges of the cheeks, nowel, and cope, by which they are attached firmly by key-bolts to resist the force of the melted metal when poured.

The operation is as follows: The side *k* of the pattern is molded in the nowel in the usual way, and turned over onto the base *l*. The sides or cheeks *b b* are then set up in place, the hinges *c c* being united. The side patterns, *m m*, are put in place with a center block to support the patterns. Parting sand is spread between *a* and *b*, and the molding-sand filled in and rammed as usual, the dowels being withdrawn, so that after the top pattern, *n*, has been molded the cope *d* may be lifted off with its pattern, then turned over, the pattern removed, the surface inspected and dressed. The sides or cheeks *b b* are then to be laid down horizontally, as seen in Fig. 4, said cheeks turning on the hinges, and the sand being supported by the cleats *g*. The respective patterns *m m* are to be removed, the surfaces

of the mold inspected and dressed. One side is then turned up into place, the sand or other core introduced and properly positioned. Then the other cheek is turned up into its former position, the cope *d* is placed on the cheeks, the parts are keyed together, and the whole is ready for casting. By this mode of opening the flask I am enabled to introduce an irregular-shaped core, corresponding to the shape of the external surface, as seen by red lines in Fig. 3, thereby obtaining the same thickness of metal throughout the casting, which is a great advantage, because, if the styles are thicker than the panels, the latter are often cracked by the contraction of the metal. If the mold were not fitted to open, as aforesaid, it will be apparent this core could not be introduced, because it is not parallel, but wider in some places than the main body of the mold.

From the foregoing description it will be understood that there is no risk of the sides not coming to their exact place, no chance of jarring and injury to the sand, and the workmen are greatly facilitated in inspecting the mold and dressing the same; hence I am enabled to produce better castings with a less expenditure of labor than with any flask before invented with which I am acquainted.

I do not claim hinging the respective parts of molds to each other, as that is well known; but

What I claim, and desire to secure by Letters Patent, is—

1. The flask for casting columns, composed of the two cheek-pieces *b b*, hinged onto the nowel *a*, and provided with the sand-cleats *g*, as and for the purposes specified.

2. The movable metallic sand-flanges *h h*, formed with dovetailed bases entering between the ribs cast on the inside faces of the cheeks *b b*, so as to be removable at pleasure, as set forth.

3. The divided cheek-pieces *b b* and clamps *ff*, fitted in the manner specified, so that the flask can be enlarged by separating said cheek-pieces and introducing a bar between said parts, as specified.

In witness whereof I have hereunto set my signature this 15th day of June, 1860:

HENRY DEMMICK.
